VACUUM CLEANER

Burgess C. Wilson, Oneonta, N. Y.

Application February 17, 1941, Serial No. 379,301

1 Claim. (Cl. 183—67)

This invention relates to vacuum cleaners and has for an object to provide a vacuum cleaner in which the air flow will not be obstructed by accumulated dirt to impair the efficiency of the suction device, this object being attained by first causing the dirt to be sucked into an air tight container and then filtering the air through an inverted filtering bag set directly over the dirt container.

A conventional vacuum cleaner accumulates all the collected dirt in a bag and due to the fact that the air is continuously passing through the dirt previously collected and the collected dirt is continuously being added to and building up more and more resistance to the air flow, the efficiency of the cleaner gradually decreases until the accumulated dirt shuts off all the air flow and the bag must be removed and emptied. When the dirt collected happens to be of a dense nature, a comparatively small amount causes this condition.

With the above in mind, the present invention provides a cleaner in which the greater portion of the indrawn dirt falls by gravity and centrifugal force to the bottom of the container and lies dormant there out of the path of the air flow, while the balance is intercepted on the walls of the filtering bag above. Each time the cleaner is shut off, the filtering bag collapses and the accumulated dirt falls into the container below and remains there, leaving the filtering bag free to pass a maximum amount of air when the cleaner is again turned on. By thus purging the air stream of the indrawn dirt, the accumulation of a greater amount of dirt is possible than with the conventional cleaner, and moreover, the cleaner remains at a high peak of efficiency through the full capacity of the container.

A further object is to provide a portable vacuum cleaner which may be easily rolled or wheeled from place to place and which will include separable sections nesting together with self-sealing joints actuated by suction when the cleaner is in operation.

A further object is to provide a device of this character which will be formed of a few strong, simple and durable parts, which will be inexpensive to manufacture, and which will not easily get out of order.

With the above and other objects in view, the invention consists of certain novel details of construction and combinations of parts herein-after fully described and claimed, it being understood that various modifications may be resorted to within the scope of the appended claim with-

out departing from the spirit or sacrificing any of the advantages of the invention.

In the accompanying drawings forming a part of this specification:

5 Figure 1 is a front elevation of a vacuum cleaner constructed in accordance with the invention.

Figure 2 is a plan view of the vacuum cleaner shown in Figure 1.

Figure 3 is a longitudinal sectional view of the vacuum cleaner, with the bag in operative position.

Figure 4 is a top plan view of the dirt container sealing ring.

Figure 5 is a bottom plan view of the filter casing sealing ring.

Figure 6 is a bottom plan view of the motor fan unit and housing.

Figure 7 is a detail sectional view showing a bonnet type baffle inclined slightly downwardly in the dirt container, which breaks the force of the indrawn dirt laden air and diverts it in the direction of the natural swirl created in the container by the action of the suction fans.

Figure 8 is an exploded sectional view showing the dirt container sealing ring, the filter casing sealing ring, and filtering bag gasket, separated.

Referring now to the drawings in which like characters of reference designate similar parts in the various views, 10 designates a rectangular base having a pair of ground wheels 11 and a caster wheel 12 for supporting the vacuum cleaner and permitting the same being wheeled or rolled from place to place.

The vacuum cleaner comprises a cylindrical container 13 adapted to be supported on the base 10. An elbow intake pipe 14 enters a sealing ring 15 for the top of the container and within the container is provided with a downwardly and laterally inclined bonnet type baffle 16. The bonnet type baffle is open at both ends and lies in the path of the natural swirl created in the container by the action of the suction fans. This bonnet breaks the force of the indrawn dirt laden air and diverts it in the direction of the natural swirl so that the collected dirt will be precipitated by gravity and centrifugal force on the bottom of the container and lie dormant there out of the path of the air flow. A conventional coupling 17 is secured to the intake pipe to facilitate the attachment of various utensils.

The upper edge portion of the container is rolled upon itself to provide a rim 18 of circular cross section. The sealing ring 15 is provided with a groove 19 which receives the rim 18, and a re-

silient gasket 20 is disposed in the groove on top of the rim. The sealing ring is provided with a second groove 21, which is formed on the top face thereof to receive a gasket 22 which will be hereinafter described in detail.

A cylindrical filter casing 23, having both ends open, is supported upon the dirt container sealing ring 15. A clamp ring 24 is disposed in the open bottom of the casing and is provided with a groove 25 which coats with the groove 21 in the dirt container sealing ring to receive the gasket 22. A dirt collecting bag 26 of porous material is mounted in inverted position in the filter casing 23 to filter dust from the air stream when the vacuum cleaner is in use. A collar 27 is secured in the mouth of the bag to hold the mouth in open position, and is provided with a pressed-in channel 28 in which the mouth of the bag is disposed and there clamped by a cord 29 or other means tied around the mouth of the bag in the channel. The lower edge portion of the collar is provided with an outwardly directed base flange 30 which is received in a groove 31 formed in the inner periphery of the gasket 22. The gasket thus forms a resilient binding, it may be called, for the mouth of the bag to hold the same sealed air-tight between the clamp ring 24 and the dirt container sealing ring 15.

Each time the cleaner is shut off, the filter bag 26 collapses into the dirt container 13 through the rigid collar 27 and remains in the container, thereby dumping the trapped dust into the container and clearing the pores of the bag for passing a maximum amount of air when the cleaner is again turned on.

The filter casing 23 is provided at the top with a sealing ring 32 having a groove 33 which receives a rolled rim 34 formed on the upper edge portion of the casing. A gasket 35 is received in the groove above the rim and forms an air tight seal at the top of the casing. The ring 32 is provided at the top face with a groove 36 which is concentric with the groove 33 and receives a gasket 37.

Superposed on the filter casing sealing ring 32 is a cylindrical housing 38 which is open at the bottom and is provided in its closed top 39 with perforations 40. A motor and fan unit 41 is supported in the housing by spiders 42. A clamp ring 43 is formed integral with the bottom of the housing and is provided with a groove 44 in the top face which coats with the groove 36 in the sealing ring 32 in receiving the gasket 37 to form an air tight seal between the housing 38 and the filter casing 23. The fan 45 sucks air through the intake pipe 14, dirt container 13, filter bag 26, filter casing 23, into the housing 38 and expels it through the perforations 40 to collect dirt and deposit it in the dirt container 13 while filtering any dust therefrom as the air stream passes through the filter bag 27 held upright in operative position in the filter casing by the air stream.

For holding the housing 38 against dislodgement from the casing 23 when the device is being wheeled to different locations, a plurality of latches 46 are pivoted on hinge ears 47 on the

housing 38 and are provided with pivotally attached hooks 48 which are engaged underneath undercut lugs 49 formed on the sealing ring 32. Likewise, latches 50 are pivoted on ears 51 carried by the filter casing 23 and are equipped with pivoted hooks 52 which engage over projecting lugs 53 on the sealing ring 32. For holding the filter casing 23 from dislodgement from the dirt container while the cleaner is being maneuvered, latches 54 are pivoted on ears 55 carried by the casing, and are equipped with pivoted hooks 56 which are engaged underneath undercut lugs 57 formed on the dirt container sealing ring 15. Likewise, latches 58 are pivoted on lugs 59 on the dirt container 13 and are equipped with pivoted hooks 60 which are engaged over projecting lugs 61 on the dirt container sealing ring.

A bail 62 is secured to the dirt container for maneuvering the cleaner.

20 Since the operation of the parts has been described as the description of the parts progressed, it is thought the invention will be fully understood without further explanation.

What is claimed is:

25 A vacuum cleaner including a cylindrical dirt container open at the top, a cylindrical casing open at its ends of smaller diameter than the container, a motor fan unit housing diametrically smaller than the casing and open at the bottom, 30 the container, casing and housing being arranged one above the other in the order named in axial alignment, a sealing ring supporting the casing on the container, a sealing ring supporting the housing on the casing, both sealing rings being 35 similar and each having a downwardly facing outer groove and an upwardly facing groove inwardly of the outer groove, the outer grooves of the sealing rings receiving upper rolled edges formed on the container and casing, gaskets disposed between said edges and the top walls of the outer grooves, an elbow extending through the sealing ring applied to the container provided with means for attaching appliances thereto, a bonnet type baffle attached at the inner opening 40 of said elbow and directed laterally outwardly and downwardly within the container to break the force of the indrawn dirt laden air and divert it in the direction of the natural swirl created in the container, an inverted dust bag, an inextensible collar having a pressed in channel receiving the mouth of the bag, a tie cord clamping the mouth of the bag in the channel to hold the bag open, a gasket secured to the collar and received in the inner groove of the sealing ring attached 45 to the container, a clamp ring secured within the lower end of the casing bearing upon the last named gasket, a clamp ring formed integral with the bottom of the housing provided with a groove registering with the upwardly facing groove on 50 the sealing ring applied to the top of the casing, a gasket in said coating grooves, and a motor fan unit within the housing creating an updraft to extend the dust bag upwardly into the casing, the dust bag collapsing downwardly into the container when the vacuum cleaner is not in use.

BURGESS C. WILSON.
